UNITED STATES PATENT OFFICE.

CHARLES H. WILLIAMS, OF WORCESTER, ASSIGNOR TO THEODORE C. BATES, OF NORTH BROOKFIELD, MASSACHUSETTS.

CORSET.

SPECIFICATION forming part of Letters Patent No. 272,179, dated February 13, 1883.

Application filed April 26, 1881. (Model.)

To all whom it may concern:

Be it known that I, CHARLES H. WILLIAMS, of Worcester, county of Worcester, and State of Massachusetts, have invented an Improvement in Corsets, of which the following description, in connection with the accompanying drawings, is a specification.

This invention in corsets has for its object the production of a corset which may be changed as to size, at pleasure of the wearer, at the hips, sides, breast, back, and waist, or either or all of these.

This my improved corset is provided at one or more places with felled or turned-in and eyeleted edges united by means of connecting-plies, which may be either of jean, canvas, elastic fabric, or any other strong and suitable material. When of jean, should it be desired to extend or expand the corset at any portion, it is only necessary to cut the connecting-plies between the eyeleted edges, and by means of cords or lacing in the eyelets hold the said edges more or less near.

Figure 1 represents a corset embodying my invention, that half of it at the left having its eyeleted edges provided with lacing-cords; Fig. 2, a section on the line xx , Fig. 1; and Fig. 3, a modification to be referred to.

Each half of the corset is composed of a back piece, a , side pieces, b c , breast gore-piece d , and front e . In the seams between the pieces b c and c d , I have placed the connecting-plies f , more or less wide or gore-shaped, as shown in the drawings, and of one or more thicknesses. The edges g of the parts, b c and c d , where joined or stitched with the connecting-plies, are turned in, as for felling or hemming, to thus conceal the raw edges, as in the section, Fig. 2, and after stitching the said felled or turned-in edges to the connecting-plies f the said edges are set with eyelets h to receive cords or ribbons i . When a piece of jean is used for the connecting-ply the eyeleted edges may be left open or unfilled, as at the right of Fig. 1, which represents the left half of the corset. Such a corset will be as firm and strong as any sewed corsets, and differs from an ordinary sewed corset only in the addition of the connecting-plies and the eyelets. The eyelets afford ventilation.

50 The connecting-plies may be cut out or removed

from between the felled or turned-in and eyeleted edges, thus making a slit or slits, f^2 , with finished and eyeleted edges, which may be held more or less separated by cords or lacings, as at the left of Fig. 1.

55 Cords or ribbons i , of any desired color, may be run into the eyelet-holes h in any of the ways shown in the drawings, adding very greatly to the appearance of the corset; or the cords or ribbons may be led through the eyelets in other order for ornamental purposes.

If desired, the lower portion of each half of the corset may be provided with two sets of connecting-plies f , as shown in Fig. 3, and of greater or less width. Cutting away these 65 connecting-plies of jean enables the corset to be enlarged at top or at bottom, should the purchaser desire, or at the waist, and if not cut the corset remains strong and firm, as if the plies f of jean were omitted and the pieces 70 composing the corset were stitched together edge to edge, as at l , Fig. 1, in usual manner.

To make the corset so that it can be used for a nursing-corset, I have slitted the top of the breast section or strip d , turned in the edges 75 of the material, and applied between the outer and inner thicknesses of the corset a breast section-ply, k , and have eyeleted the turned-in edges of the part d at h^2 to receive a ribbon, j , when desired or necessary.

80 When it is desired to convert the corset, Fig. 1, into a nursing-corset, the plies k will be cut out and the ribbons or cords j added. At other times a ribbon may be kept in the said eyelets for ornamental purposes. When cutting away 85 the parts f or k the binding m will be severed, and its ends turned in by hand and caught together with a needle and thread. These connecting-plies, for a very elastic corset, may be composed of an elastic fabric instead of the 90 unyielding, rigid jean or like inelastic cloth or fabric. The plies f k will usually be of an inelastic fabric. In Fig. 3 the corset is of a somewhat different cut, each half being composed of pieces a^2 b^2 c^2 d^2 e^2 .

95 In another application I shall show a connecting-ply extended from the bottom to the top of the corset, both at its sides and back.

In this invention it will be seen that the bust-measure of the corset, as well as its size at the 100

waist and about the hips, may be readily enlarged at the will or pleasure of the wearer. The eyelets h^2 , besides ventilating the corset, also serve as means for receiving ribbons to ornament the corset in a novel and beautiful manner, the corset being thus made more attractive and ornamental.

I claim—

1. A corset having the edges of adjacent portions of the busts or sides, or both, felled or turned in and eyeleted, as shown and described, combined with a connecting-ply applied flat therein for the purpose of being cut to permit the enlargement of the corset, substantially as specified.

2. The breast portion or bust of a corset having the eyelets h^2 and a flat ply, k , substantially as and for the purpose described.

3. A corset having flat plies applied between eyeleted edges at its sides to retain the corset in its original shape, and adapted to be cut to permit the enlargement of the corset, substantially as shown and described.

In testimony whereof I have signed my name to this specification in the presence of two subscribing witnesses.

CHARLES H. WILLIAMS.
